UNITED STATES PATENT OFFICE.

FRANK M. TAYLOR, OF SIOUX CITY, IOWA, ASSIGNOR TO THOMAS C. BRENNAN, OF NEWCASTLE, NEBRASKA, AND MAURICE W. BRENNAN, OF WYNOT, NEBRASKA.

POLISHING COMPOSITION.

1,410,041.

Specification of Letters Patent. Patented Mar. 21, 1922.

No Drawing.

Application filed April 9, 1921. Serial No. 459,989.

To all whom it may concern:

Be it known that I, FRANK M. TAYLOR, a citizen of the United States, and a resident of Sioux City, in the county of Woodbury 5 and State of Iowa, have invented certain new and useful Improvements in Polishing Compositions, of which the following is a specification.

This invention has for its object the production of an improved polishing composition particularly adapted for polishing varnished surfaces, and so compounded as to give a high lustre to the surface, yet leaving no grease thereon.

15 Furthermore the invention contemplates a polishing composition adapted to give a high lustre to varnished surfaces, which may be applied with a minimum of effort and which will not injure nor deaden the original lustre of a highly polished varnish surface.

My composition consists of the following ingredients combined preferably in the proportions stated:

	Per cent.
25 5 oz. denatured alcohol	31.25
10 oz. paraffin oil	62.5
$\frac{1}{2}$ oz. shellac (preferably white)	3.125
$\frac{1}{3}$ oz. oil of citronella	.7812
$\frac{1}{4}$ oz. alkanet root	1.5625
30 $\frac{1}{8}$ oz. oil of mirbane	.7812

The above ingredients are intimately mixed and applied to the surface preferably with a soft rag and then rubbed dry with a soft, dry rag.

Having thus described the invention, what I claim is:—

1. A surface polishing composition comprising denatured alcohol, paraffin oil, shellac, oil of citronella, alkanet root and oil of mirbane.

2. A polishing composition consisting of the following ingredients combined approximately in the per cents stated, to wit: 40 5 oz. denatured alcohol, 31.25%, paraffin oil, 62.5%, shellac (preferably white), 45 3.125%, oil of citronella, .7812%, alkanet root, 1.5625%, oil of mirbane, .7812%.

In testimony whereof I have hereunto set my hand this 16th day of March, 1921.

FRANK M. TAYLOR.
